UNITED STATES PATENT OFFICE.

FRANK HOLDRED, OF THREE OAKS, MICHIGAN, ASSIGNOR TO EDWARD K. WARREN, OF THREE OAKS, MICHIGAN.

QUILL-TREATING MACHINE.

No. 823,122.

Specification of Letters Patent.

Patented June 12, 1906.

Application filed October 13, 1905. Serial No. 282,648.

To all whom it may concern:

Be it known that I, FRANK HOLDRED, a citizen of the United States, residing at Three Oaks, in the county of Berrien and State of Michigan, have invented certain new and useful Improvements in Quill-Treating Machines, of which the following is a specification.

My invention relates to machines of that class which are employed in treating quills which are to be manufactured into what is commercially known as "featherbone," a substance designed to fill the office of flexible resilient stays in connection with various classes of dress goods. In the treatment of such quills the quill is first split and then thoroughly stripped of its contained pith, after which the split sections of the quills thus cleaned are "fibered"—that is, further split longitudinally into a number of thin narrow slivers or fibers lying side by side, with the end portions of successive bunches of fibers overlapped and intermixed, so as to create a continuous line of substantially uniform caliber, to which is applied a winding or covering of other material to mechanically bind the fibers together. Thereafter the strip thus created is specially treated to give it a uniformity of structure and strength, while preserving the natural elastic quality or resiliency of the original material.

My present invention relates to an organized machine for effecting all of the above-described operations, with the exception of the final special treatment, to secure uniformity of structure and strength and preserve the elastic quality, and pertains more especially to improvements in the means for operating the cutters which strip the pith from the split quills, said improvements having for their object to eliminate slip in the driving mechanism and to produce a machine capable of certain and uniform action through the employment of positive driving means for the said cutters.

My invention is illustrated in the accompanying drawings, in which—

Figure 1 is a top plan view of my improved quill-treating machine. Fig. 2 is a front elevational view of the same; and Fig. 3 is a top plan view of the main table or platform, showing the main line-shaft carrying a driving means for the pith-cutters, fiberizing devices, and winding-reels.

I will first briefly describe the main parts and mechanisms of the machine that directly treat the quills and will then describe those parts of the driving mechanisms therefor to which my present improvements pertain.

Referring to the drawings, 5 designates a rectangular horizontal table or platform, supported at its four corners on legs 6.

7 designates a horizontal bed-plate supported upon and above the table 5 on standards 8.

9 designates a horizontal lateral extension of the bed-plate 7, on which is mounted the quill-feeding mechanism comprising, essentially, two pairs of guide-rods 10 and 11 and a slotted guide-post 12, between which the quills are stacked, as shown at 13, said quills being pressed downwardly by a weighted overlying presser-bar 14. The post 12 has at its lower end an aperture 12^a, extending therethrough, (indicated by dotted lines in Fig. 1,) through which the quills of the stack as they successively reach the lowermost position are fed by a pair of feed-disks 15 into the nip of another pair of feed-rolls 16, located on opposite sides of the post. From 80 the grip of said rolls the quill passes directly upon the point of a knife-blade 17, whereby the quill is split longitudinally into halves. One of these halves making a turn of substantially a right angle to the right is engaged and fed between the feed-roll 16 and a companion feed-roll 18, whence it passes between the periphery of a rotary cutter-disk 19 and a guide-block 20, opposite the periphery of said cutter. On the opposite side of the knife 17 is a feed-disk 21, that co-operates with the other feed-disk 16 to carry forward the left-hand half of the split quill into the field of action of a rotary cutter 22, co-operating with a guide-block 23.

The mechanisms thus far described as lying on opposite sides of the knife are duplicates and perform similar operations upon the split halves of the quill, their function being to advance the latter and thoroughly clean it of its contained pith by the action of the cutters 19 and 22. The cutter-disks rotate in the same direction as the travel of the quill-sections, being provided with oblique peripheral teeth, which effectually eat out the body of pith contained in each half-shell.

From the pith-cutters 19 a clean half-shell passes through a tubular guide-channel 24 to

the nip of another pair of peripherally-milled feed-rolls 25, rotatably mounted on the bed-plate 7, and from the rotary pith-cutter 22 the other half of the cleaned quill-shell advances through a curved tubular guide 26 between a pair of forwarding feed-rolls 27, whence it is passed through another tubular guide 28, so disposed relatively to the companion guide 24 as to form with the latter convergent paths for the two cleaned shells to merge at the discharging ends of the guides into the nip of the feed-rolls 25, one section of quill being a half-length in advance of the other, so that said sections always overlap and break joints. From the feed-rolls 25 the cleaned half-shells of the quill pass into and through a further tubular guide 29, located beyond the feed-rolls 25, with its longitudinal axis substantially tangential to the contacting peripheries of said feed-rolls. Thence the quills travel into and through a fiberizing or slivering mechanism, (indicated at 30,) consisting, essentially, of two stacks of cutter-disks having overlapping edges on their proximate sides, by which the quills are split into fibers or slivers. The bundle of quill-stock thus fibered is divided as it emerges from the splitters into smaller bundles, which are directed, respectively, into a series of winding mechanisms, (indicated as a whole by 31,) by which a binding-cord or thread is wrapped around said bundles, thus forming a series of continuous wrapped cords or threads 32 of fibered stock. These cords 32 are wound upon a series of reels 33, that are in turn mounted frictionally upon a shaft 34, journaled in arms 35, projecting from the table or platform 5. The cords 32 are laid on the reels by suitable reciprocatory guide-pulleys 36, mounted on a shaft 37 and reciprocating thereover by a traveler engaging the usual double spiral (not shown) formed on the shaft.

The pith-cutters 19 and 22 are mounted on the upper ends of vertical shafts 38 and 39, respectively, Fig. 3, that are suitably journaled in the bed-plate 7, while one of the series of fiberizing-disks forming part of the quill-fiberizing mechanism is mounted on the upper end of a shaft 40, journaled in both the upper bed-plate 7 and the lower bed-plate or platform 5. Mounted in horizontal bearings 41 and 42, Fig. 3, on the lower bed-plate or platform 5 is the main line-shaft 43 of the machine, carrying at its overhanging end a grooved pulley 44, by which it takes its power from a driving-belt 45. Fast on the shaft 43 are a pair of oblique or spiral gear-wheels 46 and 47, that mesh with and drive similar oblique or spiral gears 48 and 49, fast on the cutter-shafts 38 and 39, respectively. Owing to the fact that the two shafts 38 and 39 do not lie in a line quite parallel with the main line-shaft 43, the coöperating gears 46 and 48 are necessarily of somewhat larger diameter

than the similar gears 47 and 49; but the same proportions are preserved between the two sets of coöperating gears in order that the speed of rotation of the two pith-cutters may be the same. Of course were the cutter-shafts 38 and 39 located the same distance from and laterally of the main line-shaft said gears would be identical in size to produce the same speed of rotation in the two cutter-shafts.

From the foregoing it will be seen that I provide a direct and positive drive between the main line-shaft 43 and the cutter-shafts, which obviates the slip that frequently occurs in belt and pulley driving means and does away with the necessity of belt-tension devices and insures a positive and uniform rotation of the cutter-shafts proportional to the speed of rotation the main line or driving shaft. This is a great advantage in a machine of this character, wherein the uniformity and value of the product is dependent upon the maintenance of the predetermined proper relative movements and speeds of the several coöperative mechanisms making up the complete machine. The pith-cutters require to be driven at a very high rate of speed, such as is usually secured through the use of belt and pulley or other frictional driving-gear; but I have discovered that by the use of the described oblique or spiral gears the required high rate of speed may be attained and maintained with absolute reliability and without any slip and yield in the driving mechanisms.

I claim—

1. In a quill-treating machine, the combination with a suitable frame, and a main driving-shaft journaled therein, of a pith-cutter, a rotatable shaft on which said pith-cutter is mounted, and spiral driving-gears between said main shaft and cutter-shaft, substantially as described.

2. In a quill-treating machine, the combination with a suitable frame, and a main driving-shaft horizontally journaled therein, of a pith-cutter, a vertical rotatable shaft on which said pith-cutter is mounted, and spiral driving-gears between said main shaft and cutter-shaft, substantially as described.

3. In a quill-treating machine, the combination with a suitable frame, and a main driving-shaft horizontally journaled therein, of means for splitting a quill longitudinally, a pair of pith-cutters serving to clean the split sections of the quill, vertical rotatable shafts on which said pith-cutters are mounted, spiral gears on said shafts, and spiral gears on said driving-shaft engaging said first-named spiral gears whereby to transmit rotary motion to said pith-cutters, substantially as described.

FRANK HOLDRED.
